UNITED STATES PATENT OFFICE.

JAMES A. HERRICK, OF NEW YORK, N. Y.

GAS-PRODUCER.

1,073,124.

Specification of Letters Patent. Patented Sept. 16, 1913.

Application filed February 4, 1911. Serial No. 606,548.

To all whom it may concern:

Be it known that I, JAMES A. HERRICK, a citizen of the United States, residing at New York, in the county and State of New York, have invented certain new and useful Improvements in Gas-Producers, of which the following is a specification.

This invention relates to the manufacture of producer gas, and one of the objects thereof is to provide a new and improved mechanical feed, or charging device for feeding fuel into the producer.

Another object is to provide new and improved stirring devices combined with the feeding apparatus, whereby the mass of fuel within the producer will be kept from clogging, and also from forming crevices or fissures in the mass.

Another object is to decrease the open space usually provided at the top of the producer, bringing the top portion thereof nearer the level of the fuel, thereby reducing the general height of the entire producer.

Another object is to provide apparatus adapted to discharge the fuel regularly and uniformly into the producer at such rates and volumes as may be necessary, and to spread the fuel evenly over the entire surface of the mass within the same.

Another object is to provide new and improved means for cutting off the passage of fuel within the producer at will, and to treat the fuel, if necessary, whereby the size of the particular lumps may be reduced before the fuel is discharged into the producer.

Another object is to provide new and improved means for preventing the escape of gases during the discharge of fuel into the producer.

Other objects will be in part obvious and in part pointed out hereinafter.

The invention accordingly consists in the features of construction, combinations of elements and arrangement of parts, which will be exemplified in the construction hereinafter described, and the scope of the application of which will be indicated in the following claims.

In the accompanying drawings, wherein I have illustrated one of the various embodiments of my invention; Figure 1 is a vertical, sectional view taken through the upper portion of the producer, constructed in

accordance with my invention; Fig. 2 is a 55 vertical, sectional view, showing the details of construction of the hopper and associated apparatus; Fig. 3 is a view of the top of the hopper, showing the cover portion; Fig. 4 is a horizontal section of a hopper, taken 60 on the line 4—4 of Fig. 2; Fig. 5 is a plan view of the lower part of the distributing or stirring device for the fuel, showing the pipe adapted to discharge water into said stirring device or shoe in section; Fig. 6 is 65 a horizontal sectional view, taken on line 6—6 of Fig. 2, showing the cut-off, or fuel regulator, interposed between the hopper and the producer; Fig. 7 is a vertical, cross-section taken on line 7—7 of Fig. 5, showing 70 the interior or circulation of the shoe or stirring device; and Fig. 8 is a partial vertical section of the hopper and top of the producer, showing the manner in which a double or duplex stirring device may be 75 attached, or operatively supported.

Similar reference characters refer to similar parts throughout the several views of the drawings.

Referring now to these drawings, A represents the top of the producer, the same, in the present instance, being constructed with upper and lower sections 2 and 3, respectively. The upper section 2 is supported as by means of legs 4, which are connected thereto as by means of struts (not shown). The producer is divided horizontally to divide the upper and lower sections 2 and 3 along the line indicated at 6, which construction permits of the lower section 3 85 being revolved by means not herein shown. In order to prevent the escape of gas from between sections 2 and 3, a suitable trough is provided at 7, the same in the present instance being a water seal of usual construction. 90

The upper, or fixed portion of the producer, as will be noted, has its side walls 8 extending over the portion 3 and depending from this overhanging portion is a 100 tongue 9, which enters trough 7, said parts in conjunction with the water, which will be contained in trough 7, constituting the seal between the relatively movable upper and lower portions of the producer. The widening of this portion of the structure, also 105 simplifies the supporting of the same by means of the struts carried by the legs 4.

Leading from the upper portion 2 of the producer is a gas discharge conduit, or up-comer 11, which is adapted to conduct the gas from the producer to the consuming apparatus.

The upper portion, or section 2 of the producer is provided with a roof 12, preferably arched, as shown, and formed centrally of this roof portion is an aperture through 10 which extends a revoluble chute or shoe 13. This chute or shoe is carried upon the shaft 14, formed of a hollow pipe, which extends upward centrally of the hopper 15, and base 16, the latter resting upon the roof portion 12 of the producer. The hopper 15 may be secured to the base portion 16 by bolts, (not shown) passing through the ears. Or such object may be accomplished by any other suitable means. The shaft 14, which is supported from its upper end by means presently to be described, is held firmly in exact central position with respect to the producer by a bearing formed centrally of the support 16, and by a similar bearing formed in 20 a support or spider located at the top and inside of the hopper 15. The upper end of shaft 14 passes through a bearing 19, suitably secured between two horizontally disposed channel beams 20, in the present instance, supported upon the legs or columns 4. The upper end of shaft 14 is provided with a bevel gear 21 suitably keyed to said shaft, said bevel gear resting upon and revolving upon an apertured block or collar 22. The block or collar 22, rests upon the 30 bearing 19, and inasmuch as bevel gear 21 is fixed firmly to the shaft 14, said shaft is supported by block or collar 22, which rests upon the bearing 19. Carried by the upper end of the shaft 14 is a bowl 23, suitably secured, as by means of a key to such shaft so as to turn with it. This bowl forms an 40 overflow for the hollow shaft.

Meshing with bevel gear 21 is a similar gear 24, upon the horizontal shaft 25 supported upon the cross-beams 20, as by means of the journaled blocks 26. Shaft 25 is provided with a second bevel gear 27, which meshes with a similar gear 28, carried by 50 the shaft 29, which in turn is carried by a block or separator 30, positioned between the cross-beams 20, and the columns 4. This shaft 29 at its lower end is provided with a bevel gear which meshes with a similar bevel gear provided upon a driving shaft, which may derive its source of power from any suitable driving means, (not shown).

In order to cool the shoe 13, and its depending stirring members, if such members 60 are provided as shown in Fig. 8, a water supply pipe 32, supplied from any suitable source of water supply under pressure, passes along over the beams 20, and is fixed by means of a suitable swivel joint 33, to 65 an upright or inlet pipe 34, which passes

down centrally of the hollow pipe 14, and terminates in one branch which passes diagonally between the walls of the shoe 13 to the toe thereof. If the stirring devices 31 are provided upon the shoe 13, then other 70 branches are formed upon the pipe 34, which extend approximately to the ends of such stirring devices, or pokers. In this manner the entire discharging and stirring apparatus will be kept in a cool condition, the 75 water passing through the entire length of the inlet pipe 34 and discharging into the shoe. The water will also flow through the branches provided in pipe 34, through the pokers or stirring members 31, the water 80 thereafter passing from the shoe 13 and said stirring members upward through the pipe 14 and overflowing into the bowl 23. The bowl at 23, it will be noted, is provided with apertures in its bottom portion, through 85 which the water drips into a depression formed in the gear wheel 21, thence flowing through nipples provided in this gear wheel into a trough carried by the bearing member 19, whence it flows off through a suitably 90 connected discharge pipe 35. Discharge pipe 35 extends along the cross beams 20, and thence down to the trough 7, the lower end thereof being connected with the trough 7, said pipe discharging the water therein. 95

Referring now to the construction of the hopper 15, the cover portion is preferably made of two independent members 35' and 36, which have a gas tight fitting one upon the other. The lower cover 35' rests tightly 100 upon the spider 18, and the top member 36 is provided with downwardly extending flanges, which embrace the outer edge of the cover member 35' and the outer edge of the hopper 15. Handles as at 35 are provided upon the cover member 36. The opening 38, shown in dotted lines in Fig. 3 provided in cover member 35' may be disposed at any desired position relative to the circumference of the hopper. By revolving cover member 35', and by revolving cover member 36, the aperture therein registers with aperture 38 of the cover member 35', thereby providing a passage way for coal into the hopper. When the hopper is filled, the top member 110 36 is rotated until aperture 38 is out of registry with the aperture in the under cover member. The ends of the arms of spider 18 are secured to the inside walls of the hopper in any desired manner as by means of 115 the counter-sunk screws shown in Fig. 2 of the drawings.

In order to stir the coal and keep it in condition to be fed into the producer, a series of horizontal spurs or arms are keyed 125 upon shaft 14. These arms, 39, are suitably spaced from each other and, preferably extend in opposite directions. The arms 39 are preferably provided with comparatively thin and slightly turned up blades. Be- 130

ween these arms, and extending inwardly from the inner wall of the hopper 15, are a series of arms or projections 39 which co-operate with the arms 39 to stir the fuel 5 within the hopper or crush the larger pieces, if necessary. The upper surface of base portion 16 of the hopper is turned off smooth and keyed to shaft 14 is an arm 41, having its underside turned to fit the upper surface 10 of base portion 16, said arm being provided with a sharp edge, so that during the rotation of the shaft 14, this arm will scrape the fuel along the surface of the base portion 16, and into the apertures 42, three of which, 15 in the present instance, are provided in said base portion. The sharp edge of the member 41 will also operate to cut in two any pieces of fuel which may be of too large a size to pass through the openings 42.

20 In the present embodiment of my invention, base portion 16 of the hopper is formed in two pieces, one of which is provided with a circular depression to receive a plate 44, provided with a projecting handle, which 25 extends through a slot provided in the apertured plate in which it rests. Plate 44 forms a gas tight joint within the base portion 16, and is provided with apertures 43, which are adapted to register with the apertures 42 of said base portion 16. It will be 30 seen that by turning member 44, the size of the apertures between the hopper and the producer may be made to increase or decrease at will or the flow of fuel may be 35 entirely shut off.

In order to insure the desired delivery of fuel upon the entire surface of the bed within the producer, two of the apertures 42 are located directly above the inclined shoe 13, 40 and the other is directly above the heel or off-set 45 of the shoe. The opening 46 of the shoe 45 is restricted so that a smaller amount of fuel is delivered directly beneath the center of the producer, than is delivered 45 upon the inclined surface of the shoe 13.

The upper surface of the shoe 13 is provided with a plurality of longitudinally extending depressions, 47, 48, 49, 50 and 51, said depressions being separated by ridges, 50 and a ridge 52 is formed adjacent the depression 51, which serves to guide the fuel as the same slides down the ridge, the surface of said shoe being inclined outwardly and downwardly, as shown. Owing to the 55 particular shape given the shoe as shown in Fig. 5 of the drawings, the depressions are of different length, that numbered 47 being shortest, and the one numbered 51 being the longest. Each of these ridges will therefore 60 discharge the coal into the producer at a point at different distance from the center of the producer, thus insuring an even distribution of the fuel upon the under surface of the mass therein.

65 Referring now to the interior construction

of the shoe 13, wherein the circulation of water is maintained, it will be noted that the interior is divided by partitions 55 and 56, the latter one being partly cut away to permit a passage of the water from one compartment to the other, water flowing first on one side and then upon the other of partitions 55 and 56. In order to insure at all times that the shoe 13 shall be filled with water to its utmost capacity, a small aperture 53 is provided in the rear portion thereof, which extends through the hollow shaft 14. This will permit the escape of any air which may be present within the shoe.

Having thus described this preferred embodiment of my invention, the manner in which it operates may now be understood.

In order to start the producer the parts to be cooled are first filled with water, in the manner already described, the fire is then started in the usual way, sufficient fuel being fed into the producer to increase the mass until the top level is at the desired height within the producer. This is accomplished by discharging the fuel from the hopper, whereupon the revolving shoe will effect an even distribution thereof upon the top of the bed. The fire is maintained within the producer in the usual way, the gas being discharged through the discharge conduit or up-comer 11.

It will accordingly be seen that I have provided a construction well adapted to accomplish, among others, all the ends and objects of the invention sought to be covered in this application.

The revolving shoe serves to make an even distribution of the fuel upon the top of the bed, and the stirring devices attached thereto constantly agitate the mass within the producer and keep the same free from fissures or crevices, thereby insuring an even quality of gas. The coal passing down through the hopper is also broken up to the desired fineness by means of the crushing means therein, and it is discharged through the openings in the bottom of the hopper, and is insured by the revolving knife which passes over the bottom wall of the hopper. The parts subjected to the heat of the turning mass are protected by means of the water circulating system, which has already been described.

Among the advantages obtained by means of the present construction is that the fuel being gradually introduced into the producer, is gradually heated before arriving at the point of gasification, thin volumes of fuel being successively formed over the entire surface of the mass.

As many changes could be made in the above construction and many apparently widely different embodiments of this invention could be made without departing from the scope thereof, it is intended that all mat-

ter contained in the above description or shown in the accompanying drawing shall be interpreted as illustrative and not in a limiting sense. It is also to be understood that the language used in the following 5 claims is intended to cover all of the generic and specific features of the invention herein described and all statements of the scope of the invention, which as a matter of language, might be said to fall therebetween.

10 Having thus described my invention, what I claim as new and desire to secure by Letters Patent, is:

1. The combination in a gas producer, of 15 a casing having an apertured cover portion, a fuel hopper carried by the cover portion above the aperture thereof, said hopper being provided with a plurality of openings in its bottom wall which lead into the producer, a shaft extending through said hopper in the central portion thereof, and a blade carried by said shaft adjacent the upper surface of the bottom wall of said hopper, said blade being adapted to break up 20 any coal lodged in the openings leading from the hopper into the producer.

2. The combination in a gas producer, of 25 a cover portion provided with a centrally located aperture, a fuel hopper mounted upon said cover portion above said aperture, the bottom wall of said hopper being provided with a plurality of openings through which fuel may be discharged into the interior of the producer, coöperating means carried by said hopper and said shaft for breaking up 30 the fuel within the hopper, and a blade carried by said shaft revolving in engagement with the bottom wall of said hopper and adapted to break up any fuel which may tend to clog said openings and thereby preventing the free discharge of fuel into 35 the producer.

3. The combination in a gas producer, of 40 a casing provided with a cover portion and a hopper, said hopper being fixed and having a bottom portion provided with an opening, a vertical shaft extending through said hopper into the interior of said casing, a fuel carrying and distributing member fixed 45 on said shaft, means for driving said shaft, and a movable member arranged at the lower end of the hopper above the distributing member and adapted during the driving of said shaft to be fixed in different positions to regulate the size of said opening.

4. The combination in a gas producer, of 50 a casing provided with a cover portion and a hopper, said hopper being fixed and having a bottom portion provided with an opening, a vertical shaft extending through said hopper into the interior of the casing, a fuel carrying and distributing member fixed 55 on said shaft, means for driving said shaft, a manually movable member disposed above said distributing member and adjacent said

opening, said last-mentioned member being provided with an opening adapted in different positions of said member to wholly and partly in different degrees register with the opening in the bottom portion of the hopper, and means for manually adjusting the aforesaid degree of registration between said openings irrespective of the driving of said shaft.

5. The combination in a gas producer, of 60 a casing provided with a cover portion and a hopper, said hopper being fixed against rotation and being provided with a plurality of openings leading into the casing, a vertical shaft extending centrally of said hopper and said openings into the interior of the casing, means for driving said shaft, and a fuel distributing member mounted on said shaft, said member being provided with a vertical opening adapted to be successively presented beneath a hopper opening and being provided with a deflector portion adapted simultaneously to be successively presented beneath a plurality of hopper openings, whereby a smaller amount of fuel 65 may be centrally distributed within the casing than is distributed away from the center.

6. The combination in a gas producer, of 70 a casing provided with a cover portion and a hopper, said hopper being fixed against rotation and being provided with an opening leading into the casing, a vertical shaft extending into the interior of the casing, means for driving said shaft, and a fuel distributing member mounted 75 on said shaft, said distributing member being hollow and being provided with interior apertured partitions whereby the same is divided into a plurality of interior chambers communicating one with another in series.

7. The combination in a gas producer, of 80 a casing provided with a cover portion and a hopper, said hopper being fixed against rotation and being provided with an opening leading into the casing, a vertical shaft extending into the interior of the casing, means for driving said shaft, a fuel distributing member mounted on said shaft, and means for delivering water within said 85 member, said distributing member being hollow and being provided with apertured partitions whereby the water may have a predetermined circulation through different portions of said member and may have 90 a passage through a plurality of interior chambers communicating successively one with the one next adjacent.

8. The combination in a gas producer, of 95 a casing provided with a cover portion and a hopper, said hopper being fixed against rotation and being provided with an opening leading into the casing, a vertical shaft extending into the interior of the casing, means for driving said shaft, a fuel dis- 100

tributing member mounted on said shaft, a main conduit for conducting water, said distributing member being hollow and being provided with interior apertured partitions dividing said member interiorly into communicating chambers, and a branch conduit leading from said main conduit into one of said chambers.

9. The combination in a gas producer, of 10 a casing provided with a cover portion and a hopper, said hopper being fixed against rotation and being provided with an opening leading into the casing, a hollow vertical shaft extending through said hopper into said casing, means for driving said 15 shaft, a fuel distributing member mounted on said shaft, said distributing member being hollow and being provided with interior apertured partitions whereby the 20 same is divided interiorly into communicating chambers, a water-feeding conduit supported within said hollow shaft and leading into one of said chambers, and a passageway leading from another of said chambers into said hollow shaft.

10. The combination in a gas producer, of a casing provided with a cover portion and a hopper, said hopper being fixed against rotation and being provided with 30 an opening leading into the casing, a hollow vertical shaft extending through said hopper into said casing, means for driving said shaft, a fuel distributing member mounted on said shaft, said distributing member being hollow and being provided 35 with interior apertured partitions whereby the same is divided interiorly into communicating chambers, a water-feeding conduit supported within said hollow shaft, a 40 passageway leading from said conduit into the interior of the distributing member, and another passageway leading from the interior of the distributing member into said hollow shaft.

45. 11. The combination in a gas producer, of a casing provided with a cover portion and a hopper, said hopper being fixed against rotation and being provided with an opening leading into the casing, a hollow vertical shaft extending through said hopper into said casing, means for driving said shaft, a fuel distributing member mounted on said shaft, said distributing member being hollow and being provided 50 with interior apertured partitions whereby the same is divided interiorly into communicating chambers, a water-feeding conduit supported within said hollow shaft and leading into one of said chambers, a 55 collection means lying in the path of the circulating water, and a leading-off conduit communicating with said collection means.

60. 12. The combination in a gas producer, of a casing provided with a cover portion

and a hopper, said hopper being fixed against rotation and being provided with an opening leading into the casing, a hollow vertical shaft extending through said hopper into said casing, a hollow fuel-distributing member mounted on said shaft, a water-feeding conduit supported within said hollow shaft and leading into said distributing member, an opening in the upper portion of said shaft for the exit of the 70 water therefrom, a bearing for said shaft, a driving element connected to said shaft said bearing and said driving element being disposed below said opening in said shaft and each said bearing and said driving element being provided with a cupped portion in the line of said shaft, and each of said cupped portions being provided with exit ports, whereby the water leaving said opening in said shaft in its gravity-impelled descent exteriorly of said shaft will have intermediate passage through said cupped portions and thereby cool the same.

13. The combination in a gas producer, of a casing provided with a cover portion and a hopper, a hollow vertical shaft extending through said hopper into the interior of the casing, means for revolving said shaft, a fuel-carrying and feeding means disposed entirely within said hopper and mounted 90 upon said shaft for revolution therewith, a hollow fuel-scattering member disposed entirely within said casing and mounted on the lower end of said shaft for revolution therewith, a hollow stirring member disposed beneath said fuel-scattering member and mounted for revolution therewith, said hollow shaft, said hollow scattering member and said hollow stirring member having 95 intercommunication, and a water-feeding 100 device carried within said shaft and adapted to cause a flow of water through all said intercommunicating parts.

14. The combination in a gas producer comprising a casing and a cover portion, or a revolvably mounted distributing member located within the producer, the upper surface of which is provided with a plurality of parallelly disposed grooves of different lengths, means for revolving said distributing member, and means for discharging fuel thereon.

15. A fuel distributing means for a gas producer, comprising a revolvably mounted hollow inclined member, the upper wall of which is provided with a plurality of longitudinally extending parallelly disposed grooves of different lengths.

16. The combination in a gas producer, of means for distributing fuel therein, comprising a hollow inclined member located within the producer, the upper wall of which is provided with a plurality of longitudinally extending grooves or depressions which operate to guide the fuel and dis-

tribute the same upon the mass within the producer at various points radially thereof, means for discharging water into the interior of said distributing member, and a plurality of partitions located within said distributing member adapted to guide the water therein therethrough.

In testimony whereof I have hereunto affixed my signature in the presence of two witnesses.

JAMES A. HERRICK.
